UNITED STATES PATENT OFFICE.

ALBERT H. EHRLICH, OF ST. JOSEPH, MISSOURI.

REGISTERING ICE DOOR.

Application filed April 23, 1923. Serial No. 633,895.

My invention relates to an improvement in registering ice-doors.

The purpose of this invention is to provide a door that will not only register the cakes of ice as they slide through the door, but will also preclude the passage of more than one cake of ice through the door at any time thus preventing the workmen from clandestine removal of cakes of ice from the storage-plant.

This invention consists in a heavy gravity door, which hangs over the door-way or passage-way, means for registering the opening and closing of the door, and a frame connected with the door which is moved into the path of the next cake of ice, in which position it is thrown by the cake of ice passing through the door.

In the accompanying drawings:—

Fig. 1 is a perspective view;

Fig. 2 is a vertical section through the door;

Fig. 3 is a similar view showing the frame in another position;

Fig. 4 is a section on line 4—4 of Fig. 3; Fig. 5 is a section on line 5—4 of Fig. 2.

The numeral 1 represents the heavy iron door suspended at the top of the door-way by the hinge 2. This door-way normally rests by gravity in a vertical position as shown in Fig. 2, where it closes the door or passage-way 3. The register 4 is mounted at some convenient point, preferably above the door, and a link 5 loosely connected with the upper end of the door is pivoted to the lever 6 which operates the register which registers each up and down movement of the door. An iron frame 7 is rigidly connected by braces 8 with the rear of the door as illustrated, and as the door 1 is swung out by the forward movement of the passing cake of ice 9, it throws the frame 7 into posi-

tion to stop the further passage of the next cake of ice 10, as viewed in Fig. 1, and in this way absolutely prevents more than one cake of ice passing through the door-way at a time.

The weight of the door 1 is sufficient to restore it to its normal position as shown in Fig. 2 by gravity. An outer door 11 closes the door-way, and this is mounted on hinges 12 and is provided with any suitable lock.

In this way a very simple means is provided for automatically counting each cake of ice with absolute accuracy, eliminating all possibility of more than one cake passing out at a time.

I claim:

1. In a device of the character described, the combination of a frame forming a passageway, a door pivoted at the upper end thereof at a point in the upper portion of the passageway and normally suspended in position to close said passageway, and a frame carried by the door and extending outwardly at an angle therefrom to be moved into said passageway upon the moving of said door therefrom.

2. In a device of the character described, the combination of a frame forming a passageway, a door pivoted at the upper end thereof at a point in the upper portion of the passageway, and normally suspended by gravity in a substantially vertical position for closing said passageway, and a frame carried by the door and extending outwardly therefrom at an obtuse angle thereto, in position to be moved into said passageway for obstructing the same upon the moving of the door therefrom.

In testimony whereof I affix my signature.

ALBERT H. EHRLICH.
